US0D1042133S

(12) **United States Design Patent** (10) Patent No.: **US D1,042,133 S**
(45) Date of Patent: ** Sep. 17, 2024

(54) **PACKAGING CARD**

(71) Applicant: **Lien Hao Chuang**, Kaohsiung (TW)

(72) Inventor: **Lien Hao Chuang**, Kaohsiung (TW)

(**) Term: **15 Years**

(21) Appl. No.: **29/861,058**

(22) Filed: **Nov. 25, 2022**

(30) **Foreign Application Priority Data**

May 26, 2022 (TW) 111302550

(51) **LOC (14) Cl.** **09-07**

(52) **U.S. Cl.**

USPC **D9/456; D19/10**

(58) **Field of Classification Search**

USPC D9/425, 432, 433, 439, 456, 455, 499;
D19/9, 10; D20/2, 10, 11, 22, 27;
D14/436, 437

CPC B65D 55/06; B65D 5/38; B65D 5/4233;
B65D 81/133; B65D 85/305; G06Q
20/3829; G06Q 20/4014

See application file for complete search history.

(57) **CLAIM**

The ornamental design for a packaging card, as shown and described.

DESCRIPTION

FIG. 1 is a perspective view of a packaging card showing our new design; and,

FIG. 2 is a front view thereof.

The broken lines are for the purpose of illustrating the environment of the design only and form no part of the claimed design.

1 Claim, 2 Drawing Sheets
